UNITED STATES PATENT OFFICE

JOHN W. WINTERICH, OF CLEVELAND, OHIO

VOTIVE STAND

Application filed January 28, 1929. Serial No. 335,465.

My invention relates to a folding stand for votive offerings, the object in general being to provide a portable stand which may be readily folded and unfolded for use with a sacred object before which votive offerings are given. To foster that purpose and at the same time increase the utility of such a device, I provide a sectional structure which may be stationed in an upright position in front of a statue or other object and folded and extended at right angles around the sides thereof. Each section is also particularly constructed to receive and hold liturgical or votive candles, preferably in stepped racks or tiers, and these stepped racks are in part also foldable to permit the end sections to be folded parallelly and compactly for convenient transport and storage, substantially as herein shown and described, and more concisely pointed out in the claims.

Thus, as exemplified in the accompanying drawings, Fig. 1 is a perspective view of my improved votive stand as it appears when folded around a statue representing a holy or godly person; Fig. 2 a perspective view of the stand partly unfolded; Fig. 3 a plan or top view of the stand folded compactly together for transportation and storage; Fig. 4 a sectional view vertically of the stand when folded as shown in Fig. 3; and Fig. 5 an enlarged view of one candle holder or rack hinged to one of the foldable side sections of the stand. Fig. 6 is an enlarged view in detail of a modified form of cup holder, and Fig. 7 is an enlarged plan view of one of the folding braces used to utilize the foldable extensions of the stand.

My improved votive stand includes a middle or main section A, and a plural number of end extensions or supplementary sections B and C, respectively, hinged thereto. Preferably, each section is an ornamental grille or open frame made of metal, and design being in keeping with or suitable for the purpose intended. These sections include one or more vertical bars or standards 2 which serve as legs or supporting members, and corresponding horizontal rails 3 which are provided with offset hinge members 4 whereby the two end sections B and C may be

folded either at an angle or parallel in respect to the middle section A, see Fig. 3. Affixed to the front of middle section A is a money box or safe 5, and projecting rearwardly and upwardly from the top rail 3 is a stepped rack D carrying a double row of holders 6 for the votive candles. Holders 6 may be of any acceptable pattern or design, and two or more rows or tiers may be used, the respective rows being situated in different vertical and horizontal planes rearwardly of the supporting frame or section A. However, the lower front row or tier of holders 6 is relatively longer than the rear upper row or tier, which arrangement is duplicated in a set of corresponding racks or tiers D'-D'' for the end sections B and C, respectively, to permit the said end sections to be folded at right angles to middle section A. When so folded the inner end of each row or tier of holders 6' on the end sections abut or form a continuation of the corresponding row of holders 6 on the front sections A and lie in the same planes therewith but at right angles thereto. Accordingly, all three sets of racks or tiers of candle holders are stepped inwardly and upwardly in respect to the statue around which the stand has been folded, and the stand has the appearance of a permanent structure capable of receiving votive offerings from the sides as well as the front thereof.

To permit the stand to be folded compactly together, end section B is hinged to section A so that it may swing to the front parallel with the front face thereof, thereby projecting its rack D' forwardly. Rack D on middle section A extends rearwardly and therefore these two racks D and D' are spaced apart from each other. However, in order that end section C may also be folded closely against middle section A, said section C is hinged to fold against the rear face of middle section A, and rack D'' on section C is hinged to one edge of its upper rail 3 to permit it to be folded downwardly upon the outer side of section C. When rack D'' is folded upwardly its flat base portion 8 rests upon the top of rail 3 so that the rack is as stably supported in an offset position as the other racks,

which are rigidly affixed to sections A and B. When the end extensions B of the stand are unfolded, say at right angles to main section A, they may be firmly braced in that position by means of foldable braces, or hook members E, see Fig. 7.

In Fig. 6, I show a modified form of cup holder comprising a set of spring fingers F riveted to the angle bar forming part of the hooks or members which are mounted upon or affixed to the folding sections. The votive candles are usually placed in suitable cups G adapted to snugly fit within fingers F.

What I claim, is:

15. 1. A votive stand, comprising foldable sections, each having votive holders affixed thereto.
2. A votive stand, comprising hinged sections, and separate tiers of votive holders for said sections.
3. A votive stand, comprising a plurality of sections hinged together, each section having a row of votive holders mounted in an offset position thereon.
25. 4. A votive stand, comprising a set of upright frames foldably connected, and stepped racks carrying votive holders mounted upon said frames.
5. A votive stand, comprising a frame carrying votive holders, and a foldable extension for said frames having a foldable rack carrying additional votive holders.
35. 6. A votive stand, comprising a main section having a stepped rack carrying votive holders, and end extensions pivotally connected to said main section having stepped racks affixed thereto and carrying additional votive holders.
7. A votive stand, comprising a main section having a tier of votive holders thereon, and foldable end sections for said main section having tiers of votive holders thereon arranged to fold at an angle in continuation of the tier of holders upon said main section.
45. 8. A votive stand, comprising a main section having stepped tiers of votive holders mounted thereon, in combination with foldable end sections for said main section having stepped tiers of votive holders mounted thereon, said stepped tiers being offset at their ends to permit said end sections to be folded at an angle to the main section.
55. 9. A votive stand, comprising middle and end sections hinged to fold and unfold, and a tier of votive holders hinged to the top of one of said sections.
60. 10. A votive stand, comprising an open frame having separate tiers of votive holders extending upwardly in offset relation thereto, and a pair of foldable extensions hinged to opposite ends of said frame, each having offset tiers of votive holders extending upwardly therefrom.
65. 11. A votive stand, comprising foldable sections having votive holders mounted thereon,

and foldable braces for connecting said sections when unfolded.

12. A votive stand, comprising angularly related sections, each having spring holders mounted thereon adapted to receive votive offerings.

In testimony whereof I affix my signature.

JOHN W. WINTERICH.
